UNITED STATES PATENT OFFICE.

HARRY E. PARSONS, OF BERWICK, PENNSYLVANIA, ASSIGNOR TO AMERICAN CAR AND FOUNDRY COMPANY, OF ST. LOUIS, MISSOURI, A CORPORATION OF NEW JERSEY.

END CONSTRUCTION FOR TANK-CARS.

1,140,707.

Specification of Letters Patent. Patented May 25, 1915.

Application filed November 22, 1913. Serial No. 802,471.

To all whom it may concern:

Be it known that I, HARRY E. PARSONS, residing at Berwick, Pennsylvania, and being a citizen of the United States, have invented certain new and useful Improvements in End Construction for Tank-Cars, of which the following is a full, clear, and exact description, such as will enable others skilled in the art to which it appertains to make and use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is a plan view of an end portion of a tank car, embodying the principles of my invention, a part of the tank being shown in section to the left of the center line and being omitted at the right thereof. Fig. 2 is a vertical longitudinal section of said end portion, on a plane substantially through the transverse center thereof. Fig. 3 is a composite view, showing at the left an end elevation of a portion of the tank car; and at the right a vertical transverse section taken along line 3—3 of Fig. 1. Fig. 4 is an elevation of the inner end of one of the unitary end castings contributing to the attainment of the objects hereinafter set forth, and Fig. 5 is a detail fragmentary view illustrating a method of connecting the running board to the unitary end casting.

As is well understood in the art of railroading, it is highly desirable to secure a low center of gravity in vehicles adapted to be rapidly drawn over rails, and it is one object of this invention to provide an end construction by which a tank car may be built which shall possess this advantage. The construction is such as to simplify the assembling of the necessary elements of the end construction, providing a structure having the essential supporting members incorporated in unitary end castings. The end construction, however, is not limited to unitary castings, as it is obvious that structural shapes or pressings may be assembled together to give the same result, and that longitudinal side and center sills may be

included to connect the end construction, together with whatever additional tank supporting means may be deemed advisable.

Another object is the utilization of the unitary end castings to form parts of the tank, as well as to operate as a supporting means therefor, the association of the tank sheets with the unitary castings being such that the tank as a whole is thoroughly sealed against leakage.

The top of the tank may, if desired, remain at the usual height, and, by reason of the bottom thereof being nearer the top of the rails than is customary, a lower center gravity may be obtained and a greater capacity for a fluid lading will result.

A further object is the anchoring of the tank at its ends by reason of the intimate relation between the tank sheets and the unitary end castings, whereby buffing stresses and lateral thrusts will be prevented from affecting the stability of the tank.

It is further to be noted that, while the construction is rugged and strong, its manufacture is relatively inexpensive.

Referring now to the drawings, A is the central or intermediate portion of a metal tank, comprising the usual lapped cylindrical sheet plates B, a curved bottom sheet 1, sheet tank heads 2 and chordal tank end bottom plates 3 of the unitary end castings 4. But one end of the tank car has been illustrated, the opposite end being identical with that shown, and the intermediate portion being merely a continuation of what is disclosed in the various figures.

Each supporting unitary end casting 4 possesses a chordal tank bottom plate 3, which is located in a higher plane than the major portion of the curved bottom sheet 1, and is so formed as to effect an indenture at each end of the middle portion of said tank, whereby the tank is enabled to occupy a lower position than is usual, and the car as a whole acquires a low center of gravity. Said bottom plate 3 is outlined by upwardly and outwardly inclined longitudinal flanges 5 and a transverse end flange 6.

The flanges are integrally formed on the casting, and those longitudinally disposed are curved to agree with the curvature of the convex surface of the end tank sheet B with which they are associated. Transverse

flange 6 inclines upwardly and outwardly and is curved to conform to the lower edge of the tank head 2.

At their inner ends, the longitudinal flanges are connected by an integral arcuated flange 7, to which is secured one end of the tank bottom sheet 1. In ordinary practice, the bottom sheet extends the entire length of the aggregated lapped tank plates B, but, in the tank car shown, each end tank plate B thereof is closed on its under side by the chordal tank bottom plate 3 of its respective end casting 4.

The inner end of the tank bottom plate 3 inclines downwardly and rearwardly, its lower edge merging with the arcuated flange 7, and results in an inclined segment-shaped wall 8. Hence, the tank of the car comprises lapped uniformly curved sheets B, tank head sheets 2, segmentally cut away on the underside, a curved bottom sheet 1, of substantially the same radius as sheets B, and which closes the gap between the extremities of all the sheets B, except the end ones, which are closed by the chordal tank bottom plates 3 of the unitary end castings 4.

The longitudinal flanges 5, transverse flanges 6 and arcuated flanges 7 afford means for making lapped fluid tight joints between the sheet metal plates and the unitary castings, which may be riveted together and caulked or welded. The tank so constructed is cylindrical in form except at each end on the underside.

35 The longitudinal flanges 5 are braced against lateral displacing influences by strengthening ribs 9, and the transverse flanges 6 are assisted in resisting longitudinal thrusts of the tank and its fluid contents by reinforcing ribs 10, all the ribs being integral parts of the casting.

Partly surrounding the chordal bottom tank plate 3, of each unitary casting, is an integral platform 11. Depending from the 45 sides of said platform 11 are short and narrow integral side sills 12 and from the end thereof a narrow end sill 13. After extending rearwardly for a material distance, the side sills 12 converge inwardly until they merge with the web 18 of an integral bolster 14, after which they continue in the plane they originally occupied at the sides of the platform 11. In the acute angles, existing at the intersection of the bolster web 18 and the inwardly inclined portions of the side sills 12, are formed push pole pockets 15.

Disposed parallel to and at equal distances from the longitudinal median line of the car, are integral draft sills 16 of angular shaped cross section. Said draft sills 16 extend from the point of intersection of the segment-shaped wall 8 with the arcuated flange 7 forwardly to the end sill 13 and intersect the web of bolster 14. End portions of car underframes are commonly

strengthened by diagonal braces, running from the intersection of the end sills and side sills at the outer corners thereof to substantially the joining point of the bolster and inner ends of the draft sills. In the 70 present structure the platform 11 performs the function of diagonal braces.

The end sill 13 is interrupted midway its length where it unites with an integral hollow buffer block 17, which is analogous 75 to and performs the same function as the well-known striking casting.

Each half of the end sill slopes rearwardly from the outer face of buffer block 17 to the side sills 12, thereby leaving angular spaces between a pair or a series of coupled cars, whereby ample clearance is afforded when said cars round a curve.

The outer ends of the draft sills also join the buffer block 17, the latter projecting into 85 and occupying the intervening space between said sills. Buffer block 17 is of a substantially inverted U-shaped vertical cross section, and in horizontal and longitudinal vertical section its walls are of angular formation. The uninclosed side at the bottom of buffer block 17 is adapted to be bridged by a carry iron, not shown, but of which there are many types in the art suitable for this purpose.

Integral bolster 14 comprises a web 18 strengthening ribs 19, a bottom flange 20, the platform 11 acting as a top flange, side bearings 21, a bolster filler 22, and a body bolster center plate 23. Through the center of said bolster filler 22 and center plate 23 extends a vertical opening 24 for the reception of the customary king bolt, and in the bolster web 18 are apertures 25 for the passage of train pipes.

The unitary end castings are connected by running boards 26, located on each side of the tank, the attachment of the latter to the former being accomplished through the use of connection plates 27, riveted, 11 bolted or otherwise secured both to the inner ends of the platforms 11 and the abutting ends of running boards 26.

What I claim is:

1. In a tank car, as an end construction, 11 a unitary casting comprising a bottom end plate of a tank integral with a bolster, a flange integral with said end plate and adapted to be secured to the head plate of a tank.
2. In a tank car, a unitary casting comprising a bolster, a bottom end plate of a tank integral with the bolster and extending horizontally and obliquely upwardly beyond 11 and around the end of the tank.
3. In a tank car, as an end construction, a unitary casting comprising a body bolster, a bottom end plate forming a portion of a tank, a vertical flange adapted to connect the bottom end plate to the head of a tank 11.

- and a side longitudinal flange adapted to connect the end side plate of said tank with the bottom end plate with which said flange is integral.
5. In a tank car, the combination of a tank, supporting unitary end castings forming the entire bottom portion of the ends of the tank each forming a portion of a bottom tank plate, a platform, a body bolster, a 10 bolster filler, an end sill and draft sills, said unitary castings being connected in the under end portions of said tank to secure a low center of gravity to said tank car.
5. In a tank car, the combination of a 15 tank comprising cylindrical sheet metal plates, a bottom plate of less length than said tank, and supporting unitary end castings each comprising an extension of said bottom tank plate but in a higher plane, said 20 unitary end castings forming a portion of the under end portion of said tank.
6. In a tank car, the combination of a 25 tank comprising cylindrical sheet metal plates, sheet metal tank heads, a metal bottom sheet of less length than said tank, and unitary end castings forming end extensions of said bottom sheet, said castings being adapted to serve as supporting means for said tank.
30. 7. In a tank car, the combination of a tank comprising curved metal plates, tank heads, a curved bottom sheet of less length than said tank, and supporting unitary end castings connected to and forming extensions of 35 said bottom sheet in a higher plane than the middle portion of said bottom sheet, thereby producing in said tank car a low center of gravity, said unitary end castings being adapted to effect the closure of the under 40 end portion of said tank and said castings each comprising a platform.
8. In a tank car, the combination of a 45 tank comprising sheet metal plates, sheet metal tank heads, a curved metal bottom sheet of less length than said tank and cast plates closing the gaps between the ends of the said bottom sheet and said tank heads, said cast bottom tank plates occupying a horizontal plane of greater altitude than the
- said bottom sheet to give said tank a low center of gravity.
9. In a tank car, the combination of a tank comprising a plurality of curved sheet metal plates, flanged sheet metal tank heads partly circular and segmentally cut away at 55 the bottom, a curved bottom sheet lapping all but the end plates, bottom tank plates constituting integral parts of supporting unitary end castings, and having upwardly extending flanges and an arcuated flange for 60 the attachment of the sheet metal elements, said bottom tank plates lying in a horizontal plane substantially in coincidence with the chord of the absent segment of said tank heads. 65
10. In a tank car, the combination of a partly cylindrical tank which is minus cylindrical segments on the under end portions thereof, unitary end castings adapted to occupy said segmentally recessed end portions 70 of said tank and support the tank, whereby said tank car acquires a low center of gravity, said unitary end castings closing openings in said segmentally recessed portions.
11. In a tank car, the combination of a 75 partly cylindrical tank which is partly composed of sheet metal plates, unitary end castings constituting parts of said tank and occupying segmentally recessed end portions thereof, each of said unitary end castings 80 comprising a horizontal bottom tank plate having a downwardly and inwardly inclined segment shaped wall merging with a transverse arcuated flange, longitudinal and transverse upstanding flanges on the horizontal 85 portion of said bottom tank plates, said flanges serving as attachment means for sheet metal tank plates and a platform; and running boards connecting the platforms of 90 said end castings.

In witness whereof I have hereunto set my hand in the presence of two witnesses this 18th day of November, 1913.

HARRY E. PARSONS.
